Primary Examiner — Mark A Goodwin*Assistant Examiner* — Benjamin M Weeks(74) *Attorney, Agent, or Firm* — Baker, Donelson,
Bearman, Caldwell & Berkowitz PC(57) **CLAIM**

The ornamental design for a webbing slide, as shown and described.

DESCRIPTION

FIG. 1 shows a perspective view of my design for a webbing slide;

FIG. 2 is a front view thereof;

FIG. 3 is a back view thereof;

FIG. 4 is a top view thereof;

FIG. 5 is a bottom view thereof;

FIG. 6 is a side view thereof; and,

FIG. 7 is another side view thereof.

1 Claim, 2 Drawing Sheets---
